(22) Filed: **Jun. 27, 2005**

The ornamental design for the holster for handheld wireless device, as shown and described.

(30) **Foreign Application Priority Data**

DESCRIPTION

Jun. 23, 2005 (CA) 111731

FIG. 1 is a front perspective view of the holster for handheld wireless device showing our new design;

(51) **LOC (8) Cl.** **03-01**

FIG. 2 is a rear perspective view of the holster;

(52) **U.S. Cl.** **D3/218**

FIG. 3 is a top view;

(58) **Field of Classification Search** D3/218,

FIG. 4 is a rear view;

D3/219, 215, 224, 226, 228, 299, 230, 249;

FIG. 5 is a left side view;

224/240, 241, 236; 206/305, 320; D14/138,

FIG. 6 is a right side view;

D14/238; 379/449, 428, 455; 455/90, 351

FIG. 7 is a front view; and,

See application file for complete search history.

FIG. 8 is a bottom view.
